UNITED STATES PATENT OFFICE.

HERBERT J. KEITH, OF FREEPORT, ILLINOIS, ASSIGNOR TO ULFERS MANUFACTURING COMPANY, OF FREEPORT, ILLINOIS, A COPARTNERSHIP.

LAMP-SHADE HOLDER.

1,374,576.

Specification of Letters Patent. Patented Apr. 12, 1921.

Application filed March 3, 1919. Serial No. 280,238.

To all whom it may concern:

Be it known that I, HERBERT J. KEITH, a citizen of the United States, and a resident of Freeport, county of Stephenson, 5 and State of Illinois, have invented certain new and useful Improvements in Lamp-Shade Holders, of which the following is a specification.

The invention relates to shade holders 10 more particularly designed for use on incandescent vapor lamps and seeks to provide a simple construction which can be economically manufactured and which is provided with adjustable means for snugly 15 engaging the neck or opening of the lamp shade to hold the latter securely in position. The invention consists in the features of improvement hereinafter set forth, illustrated in the preferred form in the accompanying drawing and more particularly pointed out in the appended claims.

In the drawing, Figure 1 is a view in elevation of the upper portion of an incandescent vapor lamp with the improved shade 20 holder applied thereto—the shade and holder being shown in section. Fig. 2 is an enlarged detail section and Fig. 3 is a plan view of the improved shade holder with the neck engaging fingers in the position 25 assumed by these parts before the shade holder is placed in use.

The improved shade holder is formed of a plate and preferably of a disk A of thin sheet metal, such as brass or soft annealed 30 steel. The disk is slightly dished or coned so as to form a flaring support, the edge portion a' of which is adapted to extend beneath the upper portion of the lamp shade B. In the construction shown, the upper 35 central portion a² of the shade holder is flattened and is provided with a central opening c. This flat upper, central portion 40 of the shade holder is adapted to rest upon the upper end portion D of the lamp, and a short threaded projection d' on the upper 45 end of the lamp extends through the opening c of the shade holder, so that a nut d² threaded on the projection can securely fasten the shade holder in position.

The shade holder is provided with a series of large ventilating openings e and also with a series of integral shade-retaining 50 fingers f. The latter are cut out of the portions of the shade holder between the 55 ventilating openings e, are radially dis-

posed and extend inwardly from points adjacent the shade supporting edge portion or flange a' of the holder. These fingers are slightly offset, when formed, as shown in Fig. 2, so that the ends may be engaged 60 and bent upwardly against the inner wall of the opening or neck b' of the lamp shade, as indicated in dotted lines in Fig. 2, and in full lines in Fig. 1.

The improved shade holder can be very 65 economically manufactured from thin sheet metal, such as brass or annealed steel, and the fingers f thereof can be readily bent to snugly engage the neck of the lamp shade, and also can be bent at different points to 70 fit neck openings of different sizes, and in this way the shade can be very securely held in position.

The supporting edge or rim a' of the shade holder, as stated, extends beneath the 75 upper portion of the lamp shade to sustain the weight thereof, while the bendable fingers f which adjustably fit within the neck 80 of the shade hold the latter against movement upon the supporting rim.

Obviously, changes may be made in the details set forth without departure from the essentials of the invention as defined in the claims.

I claim as my invention:

1. A holder for lamp shades comprising a substantially flat sheet metal disk adapted to be centrally supported upon the upper end of the lamp with its supporting rim extending beneath the upper portion 90 of the shade, said disk having a series of elongated fingers extending inwardly from its supporting rim and adapted to be bent upwardly and adjusted to snugly fit within the neck of the shade, substantially as described.

2. A holder for lamp shades comprising a sheet metal disk adapted to be centrally supported upon the upper end of the lamp with its supporting rim extending beneath the upper portion of the shade, said disk having a series of fingers cut out of the body thereof between its central and rim portions and extending inwardly from said rim portion, said fingers being adapted to 100 be bent upwardly and adjusted to snugly fit within the neck of the shade, substantially as described.

3. A holder for lamp shades comprising a sheet metal disk having a central portion 110

adapted to engage the upper end of the lamp and a flaring body portion provided with a supporting rim adapted to extend beneath the upper portion of the shade, 5 ventilating openings, and a series of radial fingers cut out of the body portion of the disk between the rim and central portions thereof, said fingers extending inwardly from said rim and adapted to be bent upwardly and adjusted to snugly fit the inner 10 wall of the neck of the shade, substantially as described.

4. A holder for lamp shades comprising a pressed sheet metal disk of conical form having a perforated central portion adapted to engage the upper end of the lamp and flaring body adapted to extend beneath the upper portion of the lamp shade, said disk having ventilating openings formed therein, and a series of radial, inwardly extending fingers adapted to be adjustably bent to snugly fit within the neck of the shade, substantially as described. 15 20

HERBERT J. KEITH.
